UNITED STATES PATENT OFFICE.

JOHN A. BRILL AND WALTER S. ADAMS, OF PHILADELPHIA, PENNSYLVANIA; SAID ADAMS ASSIGNOR TO SAID BRILL.

CAR-TRUCK.

SPECIFICATION forming part of Letters Patent No. 761,354, dated May 31, 1904.

Application filed April 4, 1900. Serial No. 11,561. (No model.)

To all whom it may concern:

Be it known that we, JOHN A. BRILL and WALTER S. ADAMS, citizens of the United States, residing in the city and county of Philadelphia, State of Pennsylvania, (and whose post-office addresses are respectively care of the J. G. Brill Company, same place,) have invented certain new and useful Improvements in Car-Trucks, of which the following is a specification.

Our invention relates to certain improvements in car-trucks generally, and more especially to the maximum-traction class of pivotal trucks.

Our invention has for its object to provide an efficient truck and one economical in construction and maintenance.

The invention therefore resides in the construction and combination of parts hereinabove described, and further pointed out in the claims.

Reference is to be had to the accompanying drawings, forming part hereof, wherein—

Figure 1 is a side elevation of a car-truck and a portion of the car-body mounted thereon. Fig. 2 is a plan view thereof. Fig. 3 is a plan view of a portion of the truck, parts being broken away; and Fig. 4 is a partly-broken end view looking from the right in Fig. 1.

Similar numerals of reference indicate corresponding parts in the several views.

Our improved car-truck is constructed as follows:

At 1 are side bars connected with yokes 2 3 at opposite ends, the yokes 2 receiving the axle-boxes 4 of the small or trailing wheels 5 and the yokes 3 receiving the axle-box 6 of the large or driving wheels 7, the truck-frame being resiliently supported upon said axle-boxes by springs 8 9 or in other well-known manner. From the yokes 3 arms 10 extend forwardly beyond the rims of the wheels 7 and are connected by a cross-bar 11, shown in the form of a T-iron set in sockets in the ends of the arms 10 and suitably secured.

The side bars 1 are connected by a cross-bar 12, which may be suitably secured to said side bars, whereby the side bars are braced later-

ally. From the yoke 3 an arm 13 extends forwardly above the arm 10, and 14 is a web that extends from the front edge of yoke 3 upwardly and under the arm 13, whereby the parts 3 and 13 are stiffened and braced.

The arm 13 is braced in connection with the cross-bar 11 by means of a brace 15, that is shown provided with a bifurcated end that receives the web 14, to which it is bolted or riveted, and the brace 15 is curved inwardly and its lower end is bent downwardly and secured by suitable means to the cross-bar 11.

From the part of yoke 3 opposite the arm 13 an arm 16 extends rearwardly of the truck, and 17 is a web that extends from the yoke 3 along under the arm 16 to strengthen and brace said parts. The arm 16 is braced in connection with the cross-bar 12 by means of a brace 18, shown bifurcated at its upper end and riveted or bolted to the web 17, its lower end being bent inwardly and suitably secured to bar 12.

The arms 13 and 16 at their ends are raised above the central portion thereof, and at said ends they are widened out and provided with top depressions, in which the end portions of a horizontally-disposed leaf-spring 19 lie. (See Figs. 1 and 4.)

The spring 19 is connected with the arm 16 by means of yokes 20, that inclose the strap 21 of the spring, the lower ends of said yokes passing through lugs 22 on opposite sides of arm 16 and being provided with nuts to hold the spring 19 firmly upon the arm 16. The ends of the spring are thus free to vibrate vertically in the depressions at the ends of arms 13 16, and the side walls of said ends of the arms resist lateral movement of the spring.

It will be seen that the connection of spring 19 with the truck is close to a vertical line passing through the axle 7^a of the driving wheels 7, whereby a maximum-traction truck is produced.

The springs 19, one at each side of the truck, are connected at their ends by cross-bars 23 24, which form a car-supporting means comprising a plurality of spaced members. These bars are shown in T form in cross-section (see Fig. 1) and may be connected with the

springs 19 in suitable manner. We have shown the bars provided near their ends with clips or socket-pieces 25 26, whose recesses or sockets follow the outline of the bars 23 24 (see Fig. 1) and are secured thereto, as by bolts passing through the depending webs of said clips and the depending web of the bar. From the upper surface of the clips 25 26 project eyes 25^a 26^a, arranged in pairs (see Fig. 4) and receiving between them a pin 27 28, upon which the corresponding end of spring 19 is coiled. Thus the cross-bars are pivotally connected with the ends of spring 19 to allow for vertical movement of the bolster relatively to the spring, and as this bolster extends across the truck it serves as a support for the car-body to resiliently support the same from the springs 19, the bars or bolsters being located eccentrically of the wheel-base center of the truck, the bar 23 being located adjacent the axle of the driving-wheels and adjacent to which wheels the pivotal center of the truck is located, thereby providing an eccentrically-pivoted truck and the imposition of the car-load thereon adjacent the driving-wheels, both desirable features in trucks of this class. As a specific means of carrying out the foregoing the bar or bolster 23 is located outside the wheel-base.

30 The cross-bars 23 24 are provided with bearing-plates 29 30, which are secured centrally upon the top surface thereof, upon which rest bearing-plates 29^a 30^a, that are carried by the car-body, the latter plates being curved on an arc derived from the pivotal center of the car-truck. (See Fig. 2.) The plates 29^a 30^a may be secured to the car-body in any suitable manner, and they are shown secured to and beneath cross sills or beams 31 32 of the car-body.

35 The sills 31 32 are shown extending between longitudinal intermediate sills 33 of the car-body, and for the purpose of strengthening the same we provide longitudinally-extending plates or bars 34, that are secured to the inner face of the sill 33, and the ends are bent sidewise and lie against the corresponding portion of sills 31 32, to which said ends are suitably secured, all as shown in Fig. 2.

40 To assist in holding the small wheels 5 down upon the track, or, in other words, to keep them from jumping, we provide the following arrangement: The cross-bar 12 is shown bent outwardly at its center portion 12^a toward the axle 5^a of the small wheels, (see Fig. 3,) and upon said bent portion rests a spring-cup 40, through which a guide-rod 41 passes, the spring-cup being retained upon the bar 12 by a strap or the like 42, and 43 is a spring 45 coiled around the rod 41 and resting upon cup 40. Beneath the head 41^a of rod 41 is a spring-cap 44, resting upon spring 43, whereby rod 41 is sustained by spring 43, and said spring resists the downward movement of said 50 rod. Upon the head 41^a of rod 41 a plunger

or wear-plate 45 rests, and this is guided in a bushing or bearing 46, carried by cross-bar 24. A bearing-plate 47, carried by the car-body, rests upon plunger 45, (see Fig. 4,) and the under surface of this plate is shown cam-like, or, in other words, it diverges downwardly and outwardly from its central point 47^a, and this central point or the high part of the plate 47 is so located that when the truck is in proper alinement with the car-body the 75 plunger 45 will rest therein. (See Fig. 4.) Thus if the small-wheel end of the truck tends to rise from the track it will meet the resistance of the parts 41 43 45 47 and the car-body, and as the truck swivels under the car-body 80 the cam-surfaces of the wear-plate 47 will cause spring 43 to exert increased pressure upon the cross-bar 12 to further assist in preventing the small wheels from jumping from the track.

85 We have shown improved means for a drawing connection between the truck and the car-body, which are arranged as follows: At 50 is a draw-bar connected with cross-bar 23 and with a sill or bar 51 of the car-body. This 90 draw-bar is shown as bifurcated or provided with two arms attached to cross-bar 23, as by rivets, bolts, or the like, and at its opposite end it is provided with a head portion 50^a, that has an aperture through which a drawing-pin 95 52 passes, said pin being connected with the part 51 of the car-body. The head portion 50^a of the draw-bar is shown as extending horizontally beneath the car-body, and the arms of the draw-bar are shown as bent downwardly and forwardly toward the cross-bar 23, whereby the pivot 52 is elevated above said cross-bar. The arrangement we have shown for supporting the pivot 52 comprises the sill or cross-bar 51, having its ends 51^a 100 bent downwardly and attached to the intermediate longitudinal sills 33 of the car-body, (see Fig. 4,) and 53 is a strap secured to the under side of sill or bar 51 and bent downwardly at its central portion 53^a, forming a 105 space 54, in which the head 50^a of the draw-bar is located (see Fig. 4) and wherein it has lateral pivotal movement. Thus it will be seen that as the truck is propelled it will draw the car-body through the medium of the draw-bar, or vice versa, and that as the car-body is supported upon the cross-bar 23 and the draw-bar 50 is also connected to cross-bar 23 and to the car-body the vertical movements of the body upon springs 19 will be coextensive with the vertical movement of the draw-bar, and thus no undue strain will be applied to the draw-bar through the movements of the car-body.

110 115 120 125 We do not limit our invention to the details of construction shown and described, as they may be varied without departing from the spirit thereof.

Having now described our invention, what we claim is--

1. The combination in a car-truck, of a car-supporting means, the car-body above said means, a horizontally-disposed leaf-spring support for said means, and a draw-bar connected with said means and with said car-body. 70
2. The combination in a car-truck, of a car-supporting means comprising a plurality of spaced members, a car-bearing carried thereby, a horizontally-disposed leaf-spring support, for said means, supported by the truck-frame, and a draw-bar extending from said means adjacent said bearing, and adapted to be secured to a car-body. 75
- 15 3. The combination in a car-truck, of a transversely-extending car-supporting means having a car-bearing, a horizontally-disposed leaf-spring support for the said means supported by the truck-frame, and a draw-bar extending from the said means adjacent one of said bearings, and adapted to be secured to a car-body. 80
- 20 4. The combination in a car-truck, having a frame, of horizontally-disposed leaf-spring supports, a bolster on said supports, the spring-supports and bolster constituting car-supporting means, a car-body above said bolster, and a draw-bar connected with the bolster and with the car-body. 85
- 25 5. The combination in a car-truck of a car-supporting means extending across the truck, comprising a plurality of spaced members, a horizontally-disposed leaf-spring support for said means, and a draw-bar connected with said means and adapted to be secured to a car-body. 90
- 30 6. The combination in a truck having a car-supporting means extending across the truck of a horizontally-disposed leaf-spring support for the said means, said spring-support being supported upon the truck-frame, and a draw-bar connected with said means and adapted to be secured to a car-body. 95
- 35 7. The combination in a car-truck having large and small wheels, of a truck-frame, a car-supporting means comprising a plurality of spaced members, a horizontally-disposed leaf-spring support for said means, the said means and spring-support being located adjacent the driving-wheels, and a draw-bar connected with said means and adapted to be secured to the car-body. 100
- 40 8. The combination in a car-truck having large driving-wheels and small trailing wheels, of a truck-frame, a transversely-disposed car-supporting means, a horizontally-disposed leaf-spring support for said means, the said means and spring-support being located adjacent the driving-wheels, and a draw-bar connected with said means and adapted to be secured to a car-body. 105
- 45 9. The combination in a car-truck having large driving and smaller trailing wheels, a truck-frame, a car-supporting means comprising a plurality of transversely-disposed spaced members, a horizontally-disposed leaf-spring support for the said means, said means and spring-support being located eccentrically of the truck-wheel-base center and adjacent the driving-wheels, and a draw-bar connected with said means and adapted to be connected with a car-body. 110
- 50 10. The combination in a truck having large driving and small trailing wheels, a truck-frame, a transversely-extending car-supporting means, a horizontally-disposed leaf-spring support for the said means, said means and spring-support being located eccentrically of the truck-wheel-base center and adjacent the driving-wheels, a car-body, and a draw-bar connected with the said means and with the car-body. 115
- 55 11. The combination in a car-truck having large driving and small trailing wheels, of a truck-frame, a car-supporting means comprising a plurality of transversely-disposed spaced members, a horizontally-disposed leaf-spring support for said means supported on the truck-frame, the said means and spring-support being located nearer the driving than the trailing wheels, and a draw-bar extending from said means toward the axle of the driving-wheels. 120
- 60 12. The combination in a truck having large driving-wheels and small trailing wheels, of a truck-frame, a transversely-disposed car-supporting means, a horizontally-disposed leaf-spring support for said means supported on the truck-frame, the said means and spring-support being located nearer the driving than the trailing wheels, and a draw-bar extending from the said means toward the axle of the driving-wheels. 125
- 65 13. The combination in a car-truck having large driving and small trailing wheels, of a truck-frame, a bolster, a centrally-located car-bearing carried by said bolster, horizontally-disposed leaf-spring-supporting means interposed between said truck-frame and bolster, the bolster and supporting means being located nearer the driving than the trailing wheels, and a draw-bar extending from the bolster toward the axle of the driving-wheels and having a pivot in line with said car-bearing. 130
- 70 14. The combination in a truck having large driving and small trailing wheels, of a truck-frame, a transversely-disposed car-supporting means having a centrally-located car-bearing, a horizontally-disposed leaf-spring support for the said means on the truck-frame, the said means and spring-support being located nearer the driving than the trailing wheels, and a draw-bar extending from the said means toward the axle of the driving-wheels, and having an outer pivot in line with said car-bearing. 135
- 75 15. The combination in a car-truck, having large driving and small trailing wheels, of a truck-frame, a car-supporting means comprising a plurality of transversely-disposed spaced members, a horizontally-disposed leaf-spring support for the said means, said means and spring-support being located eccentrically of the truck-wheel-base center and adjacent the driving-wheels, and a draw-bar connected with the said means and with the car-body. 140

- ing a plurality of transversely-disposed spaced members, a horizontally-disposed leaf-spring support for said means, the said means being located eccentrically of the truck-wheel-base 5 center and adjacent to the driving-wheels, a draw-bar extending from the said means toward the axle of the driving-wheels, and means for securing a car-body to the free end of the draw-bar.
16. The combination in a car-truck having large driving and small trailing wheels, of a truck-frame, a transversely-disposed car-supporting means, a horizontally-disposed leaf-spring support for the said means, the said 10 means being located eccentrically of the truck-wheel-base center and adjacent the driving-wheels, a draw-bar extending from the said means toward the axle of the driving-wheels, and means for securing a car-body to the outer 15 end of said draw-bar.
17. The combination in a car-truck, having large driving and small trailing wheels, of a truck-frame, a car-supporting means comprising a plurality of transversely-disposed spaced 20 members supported by a horizontally-disposed leaf-spring support on said truck-frame eccentrically of the truck-wheel-base center and adjacent to the driving-wheels, and a draw-bar extending from said car-supporting means adjacent to the axle of the driving-wheels.
18. The combination in a truck having large driving-wheels and small trailing wheels, a truck-frame, a cross-bolster spring-supported from the truck-frame outside the wheel-base 25 and adjacent the driving-wheels, and a draw-bar extending from the said bolster toward and adjacent the axle of said driving-wheels.
19. The combination of a truck having large driving-wheels and small trailing wheels, a truck-frame, horizontally-disposed leaf-spring supports forming part of the truck-frame, a bolster having a car-bearing spring-supported from the spring-support outside the wheel-base and adjacent the driving-wheels, the 30 spring-support and spring-supported bolster constituting car-supporting means, and a draw-bar extending from said car-supporting means toward and adjacent the axle of the driving-wheels.
20. The combination of a truck having large driving-wheels and small trailing wheels, a truck-frame, a bolster having a centrally-located car-bearing, horizontally-disposed spring-supports forming part of the truck-frame, horizontally-disposed leaf-springs secured to the spring-supports, the bolster, 35 springs, and the spring-supports being located nearer the driving than the trailing wheels and constituting car-supporting means, and a draw-bar extending from said car-supporting means toward and adjacent the axle of said driving-wheels.
21. The combination in a truck having large driving-wheels and small trailing wheels, a truck-frame, a cross-bolster spring-supported 40
- from said truck-frame outside the wheel-base and adjacent the driving-wheels, a car-bearing on said bolster and located within the pivotal radius of the truck, and a draw-bar extending from said bolster toward and adjacent the axle of said driving-wheels and in line with said car-bearing. 45
22. In a car-truck having large driving-wheels and small trailing wheels, the combination with a truck-frame, a bolster spring-supported on said frame eccentrically of the wheel-base center, and adjacent the driving-wheels, a draw-bar extending from the bolster toward the axle of the driving-wheels, and means for pivotally securing a car-body to the inner end of said draw-bar. 50
23. In a car-truck having large driving and small trailing wheels, the combination of a truck-frame, a bolster spring-supported upon said frame eccentrically of the wheel-base center and adjacent the driving-wheels, a car-bearing supported by said bolster within the pivotal radius of the truck, a draw-bar extending from the bolster toward the axle of the driving-wheels, and means for pivotally securing a car-body at the inner end of said draw-bar located in line with said bearing. 55
24. In a car-truck having side bars, axle-box yokes, arms extending forwardly from certain of said yokes, cross-bars connecting said arms and connecting the side bars, arms extending in opposite directions from the upper portion of said yokes, and braces connecting said arms with said cross-bars. 60
25. In a car-truck, the combination of the side bars, axle-box yokes, and arms extending in opposite directions from said yokes, with springs overlying said arms and supported thereon, and means for supporting a car-body on said springs. 65
26. In a car-truck, the combination of side bars, axle-box yokes and arms extending in opposite directions from said yokes, said arms having central depressed portions and upwardly-extending ends provided with top depressions, with springs located in said central depressions and secured to one set of said arms, the outer portions of said springs being located in the depressions in the ends of the arms, and means for supporting a car-body on said springs. 70
27. In a car-truck, the combination of side bars, axle-box yokes and arms projecting from said yokes in opposite directions, lugs projecting from one set of said arms, springs mounted above said arms, and yokes connecting said springs with said lugs, with means for supporting a car-body upon said springs. 75
28. The combination of a car-truck having axle-box yokes and arms extending in opposite directions therefrom, with longitudinally-disposed leaf-springs supported by the arms, and cross-bars connecting the corresponding ends of said springs. 80
29. The combination of a car-truck having 85

axle-box yokes, and arms extending in opposite directions therefrom, with longitudinally-disposed leaf-springs supported by the arms, cross-bars connecting the corresponding ends

5 of said springs, and means for movably supporting a car-body upon said cross-bars.

30. The combination of a car-truck having axle-box yokes provided with arms extending in opposite directions, with springs carried 10 by said arms and cross-bars pivotally connected with the corresponding ends of said springs.

31. The combination of a car-truck having axle-box yokes provided with arms extending 15 in opposite directions longitudinally of the truck, with leaf-springs secured to said arms and extending longitudinally of the truck, cross-bars connecting the corresponding ends of said springs, and means for supporting a 20 car-body upon said cross-bars.

32. The combination of a car-truck having axle-box yokes provided with arms extending in opposite directions, with longitudinally-disposed leaf-springs carried by said arms, 25 cross-bars, and clips movably connected with said springs and also connected with said cross-bars.

33. The combination of a car-truck having leaf-springs attached thereto and extending 30 longitudinally thereof, clips pivoted to the ends of said springs, and cross-bars secured to said clips.

34. The combination of a car-truck having leaf-springs extending longitudinally thereof 35 at opposite sides, a T-shaped cross-bar, clips having socket portions corresponding in cross-section to said bars, receiving the same and secured thereto, and means for supporting said clips upon said springs.

40. 35. The combination of a car-truck having leaf-springs attached thereto and extending longitudinally thereof, clips having eyes projecting upwardly therefrom, pins or bars located in said eyes, the ends of said springs being pivoted upon said pins or bars, and cross-bars connected with said clips.

36. In a car-truck, the combination of a cross-bar secured to its side bars and having a rearwardly-bent portion at its center, with a 50 spring mounted upon said bent portion of the cross-bar, a rod passing through said spring and guided upon the cross-bar, and means interposed between said rod and a car-body whereby the upward thrust of the spring is 55 resisted.

37. In a car-truck, the combination with the cross-bar connected with the side bars of the truck, a spring-cup connected with said cross-bar, a bar through the said spring-cup, a 60 spring surrounding said rod and resting upon the cup, an abutment secured to the rod between the upper part of the rod and said spring, a body cam-plate having surfaces converging inwardly and upwardly and merging

over said rod, and means having a converging 65 upper surface interposed between said rod and the cam-plate, and carried by the rod for resisting the thrust of the rod.

38. In a car-truck, the combination of longitudinally-extending springs and cross-bars 70 connected with said springs, with a cross-bar connecting the side bars of the truck, a spring supported by said cross-bar, a rod passing through said spring, a wear-plate carried by the car-body, a plunger in line with said rod, 75 and a guide for the plunger carried by the side-bar-connecting cross-bar.

39. In a car-truck having a frame and axle-box yokes, the combination of a pair of leaf-springs arranged longitudinally with respect 80 to the yokes, and a cross-bar connecting them beyond the yokes, a draw-bar connected with the cross-bar, a car-body mounted upon said cross-bar, and connections between the car-body and the draw-bar.

40. In a car-truck, having a frame and axle-box yokes, the combination of leaf-springs arranged longitudinally with respect to the yokes, a cross-bar connecting said springs beyond the yokes, with a car-body mounted upon 90 the cross-bar, a draw-bar connected with the cross-bar and provided with a head having an opening, and a pivot-pin connected with the car-body and passing through the opening in said head.

41. In a car-truck having a frame, and axle-box yokes, the combination of the leaf-springs longitudinally disposed relative to the yokes, a cross-bar connecting said springs beyond the yokes, with a car-body mounted upon the 100 cross-bar, a bifurcated draw-bar having its arms attached to the cross-bar and having a head provided with an opening and a pivot-pin carried by the car, and passing through the opening in said head.

42. In a car, the combination of a truck having springs and a cross-bar connecting said springs, with a body mounted upon said cross-bar, a draw-bar connected with said cross-bar, a bar carried by the car-body and having 110 a strap forming a space between them in which the head of the draw-bar lies, and a pivot-pin carried by said cross-bar and strap passing through the head of the draw-bar.

43. In a car, the combination of a truck, a 115 pair of leaf-springs carried by and extending longitudinally thereof, cross-bars connecting said springs, and wear-plates carried by said cross-bars, with a car-body having wear-plates mounted upon the first-mentioned wear-plates. 120

44. The combination in a car-truck of the maximum-traction type, having large and small wheels, and a frame therefor having axle-box yokes or pedestals, a leaf-spring at each side longitudinally disposed over the side 125 frames and pedestals adjacent the large wheels, a car-body-supporting cross-bar extending between the side frames of the truck and in part

supported on the inner ends of said springs, and another spring supported on the truck-frame in part supporting said cross-bar.

45. The combination in a car-truck of the maximum-traction type, having large and small wheels, and a frame therefor having axle-box yokes or pedestals, a leaf-spring at each side longitudinally disposed over the side frames and pedestals adjacent the large wheels, 5 a car-body-supporting cross-bar extending between the side frames of the truck and in part supported on the inner ends of said springs, and other springs supported on the truck-frame in part supporting said cross-bar, said latter spring-support being located on a cross-bar of the truck extending between the side frames adjacent the small wheels.

46. The combination in a car-truck, a frame therefor, centrally-supported leaf-springs disposed longitudinally above the side members of the frame, and having their ultimate sup-

port on the axle-boxes, a plurality of cross-bars supported by said springs adjacent their ends, and means for supporting a car-body carried by said cross-bars.

25

47. A car-truck having side frames, a leaf-spring disposed longitudinally over each of the side frames, a transverse bar supported by said springs and movably connected with the ends thereof, a bearing over said bar adapted to act with a car-body, and a draw-bar extending from the bar adapted to be secured to a car-body.

Signed at the city and county of Philadelphia, State of Pennsylvania, this 8th day of January, 1900.
